PRELOADING APPARATUS FOR PRINTING PRESSES

Joseph F. Jirousek, Cleveland, Ohio, assignor to
 The Chandler & Price Company, Cleveland,
 Ohio, a corporation of Ohio

Application September 21, 1938, Serial No. 231,034

7 Claims. (Cl. 271—62)

This invention relates as indicated to preloading apparatus for printing presses, but has reference more particularly to apparatus of this character which has been designed for use in connection with printing presses of the type illustrated in my co-pending patent application Serial No. 183,476.

A primary object of the invention is to provide apparatus whereby the sheet feeding table of the printing press may be loaded in a position which is readily accessible as compared with the normal position thereof relative to the press.

Another object of the invention is to provide means whereby the loaded feed table of the press may be moved from the loading position to the normal position, i. e., the position wherein it may be elevated by such sheet feeding means.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of a portion of a printing press showing the preloading apparatus and parts of the feed table elevating means whereby such apparatus cooperates; Fig. 2 is a side elevation of the apparatus shown in Fig. 1; Fig. 3 is a longitudinal cross-sectional view taken on the line 3—3 of Fig. 1; Fig. 4 is a transverse cross-sectional view taken on the line 4—4 of Fig. 3; Fig. 5 is a transverse cross-sectional view taken on the line 5—5 of Fig. 2; Fig. 6 is a fragmentary enlarged cross-sectional view of the latching mechanism shown in Fig. 3; Fig. 7 is a fragmentary view of a portion of the preloader as viewed from the right of Fig. 2; Fig. 8 is a perspective view of one of the feed table gauges.

Referring more particularly to the drawings, the printing press for which the present apparatus has been designed comprises a frame 1 having at opposite sides thereof endless conveyor chains 2 to the inner runs of which are secured brackets 3. These brackets support a feed table elevator comprising a substantially rectangular frame consisting of side members 4 and front and rear members 5, the intermediate portions of the front and rear members being depressed a considerable distance below the plane of the members 4, so as to provide space for the entrance of certain parts of the preloader, as will be presently described.

Arranged within the aforesaid frame are stands adapted to temporarily support the feed table of the press. Such stands comprise spaced legs

6 and bridging pieces 7, the upper surface of the pieces 7 being at a level intermediate the level of the elevator members 4 and depressed portions of members 5, and the legs 6 being rigidly secured to the floor of the room in which the press is located.

The preloader proper comprises a frame 8 having legs 9 to which are secured castors 10 whereby the preloader may be freely moved about on the floor of the room adjacent the press.

Mounted on the cross members 8a of the frame 8 are gibs or tracks 11 upon which are slidably supported the side members 13 of the feed table supporting frame, such frame including in addition to such side members longitudinally spaced cross rods 14. Journalled in the forward ends of the side members 13 are rollers 15, the function of which will be presently described. The side members 13 are formed at their lower edges with rack teeth 16 and are provided on their upper edges with rear gauge pins 17 and side gauge pins 18 for the sheet feeding table 19 of the press. The table 19 has openings in its lower surface into which the pins 18 extend whereby the table may be gauged laterally, the pins 17 gauging said table rearwardly. The rack teeth 16 are in engagement with pinions 20 which are keyed to a cross shaft 21 journalled in the frame 8 of the preloader.

Secured to one end of the shaft 21 is a large gear 22, rotation of which, for the purpose of causing the frame 13—14 to be moved along the gibs 11, is effected by means of a pinion 23 which is keyed to a shaft 26. Shaft 26 is slidably mounted in a tubular member 27 which is journalled in the frame 8 of the preloader. The shaft 26 is provided with a pin 28 which is movable along a slot 29 of the tube 27 so that the shaft 26 may be moved to the dotted line position shown in Figs. 1 and 5, without disturbing the driving connection between the gears 22 and 23, it being noted at this point that the pinion 23, which is keyed to the tube 27, is not moved outwardly when the shaft 26 is moved to the dotted line position. The shaft 26 is adapted to be rotated by means of a crank 24 secured to the outer end thereof and provided with a handle 25.

In order to prevent displacement of the members 13 from the gibs 11 as such members are moved along the gibs, such members have secured thereto at the rear ends retainers 30 having inturned flanges 31 which engage the under sides of the gibs (see Fig. 7). Stops 12 are secured to the rear ends of the gibs 11 and these serve to limit the rearward movement of the members 13.

Pivots secured to the frame 8 of the preloader as by means of a horizontally disposed pin 32 is a hinge member 33, which when in horizontal

60

position as shown in solid lines in Fig. 5, may be pivotally connected as by means of a hinge pin 34 to a hinge member 35 secured to the frame 1 of the press. By means of such hinge connection, 5 the preloader may be moved laterally of the press to a position wherein the feed table 19 thereof can be easily loaded with the stack of sheets S to be printed.

Upon swinging the preloader back to the position shown in Fig. 1, the preloader is maintained in such position by means of a latch designed to engage keepers 36 depending from the depressed portions of the rear members 5 of the sheet elevator frame. The latch comprises a latching 10 member 37 having a curved cam face 38, such member being pivoted as at 39 to a bracket 40 secured to the front cross member 8a of the frame 8 of the preloader. Secured to the upper end of the bracket 40 is a horizontally extending 15 member 41, between which and a similar member 42 secured to the latching member 37, is interposed a coil spring 43, such spring tending to normally hold the latching member 37 in the horizontal position shown in Fig. 6. Upon movement 20 of the preloader to the position shown in Figs. 3 and 6, the cam face 38 of the latching member strikes the keeper 36, the latching member being thereby depressed against the action of the spring 43, the parts finally assuming the 25 position shown in Fig. 6.

Temporary front gauges 44 having feet 45 are secured to the front edge of the feed table 19 as by entering the feet 45 in holders 46 secured to the lower face of the table adjacent said front 30 edge.

For the purpose of gauging the front edge of the stack S with reference to the printing press proper, a series of vertically extending gauges 48 is provided which gauges are secured to a cross 40 member 47 secured to the frame 1 of the press. Stops 49 are secured to the front of the preloader frame for the purpose of limiting the movement of the preloader with reference to the elevator frame 4-5 of the press.

Having thus described the constructional features of the preloader and the parts of the press with which the preloader is designed to cooperate, the operation of the preloader may now be briefly described.

The preloader is swung to a position laterally of the press and the feed table 19 is placed therein in properly gauged position with reference to the pins 17 and 18, the gauges 44 being also in position. A stack of sheets S is then placed on the table with the forward edge of said stack engaging the gauges 44, it being understood that the stack is also gauged laterally by any suitable means.

The preloader is then swung to the latched position shown in Figs. 1 and 2, and the crank 24 is then rotated so as to cause the members 13 to be moved inwardly towards the press, the rolls 15 riding onto the bridging pieces 7, and serving to enable the feed table to just clear the frame 4-5, as shown in Figs. 3 and 4, the members 13 finally assuming the position shown in Fig. 3. The chains are then moved so as to lift the feed table 19 off the members 13, after which the rack members 13 are retracted to their original position. The frame 4-5 bearing the feed table, is then moved upwardly to the working position of the feed table. In the upward movement of the

feed table, the keepers 36 move clear of the latching members 37, so that the preloader may be swung away from the press for further loading.

If desired, the hinge pin 34 may be withdrawn and the hinge member 35 dropped to the dotted line position in Fig. 5, after which the preloader may be moved to any desired position away from the printing press.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a printing press, a frame, feed table elevating means, a feed table, a feed table support movable laterally of said frame to a position wherein the sheets to be printed may be placed on said feed table, and means for latching said feed table support to said feed table elevating means.

2. In a printing press, a frame, a feed table, feed table elevating means, a feed table support movable laterally of said frame and away from said elevating means to a position wherein the sheets to be printed may be placed on said feed table, and means for temporarily latching said feed table support in position for elevation of said feed table by said feed table elevating means.

3. In a sheet feeding device for printing presses, a feed table, feed table elevating means, means for temporarily supporting said feed table in position to be engaged by said elevating means, a feed table support movable laterally of said temporary supporting means and rack means for transferring said feed table from said support to said temporary supporting means.

4. In a printing press, a frame, a feed table, a feed table support hinged to said frame and movable to a position laterally of said frame, feed table elevating means, means for temporarily supporting said feed table in position to be engaged by said elevating means, and means for transferring said feed table from said support to said temporary supporting means.

5. In a printing press, a frame, a feed table, a feed table support hinged to said frame and movable to a position laterally of said frame, feed table elevating means, means for temporarily supporting said feed table in position to be engaged by said elevating means, and rack means for transferring said feed table from said support to said temporary supporting means.

6. In a printing press, a frame, feed table elevating means, a feed table, a feed table support movable laterally of said frame to a position wherein the sheets to be printed may readily be placed on said feed table, and rack and gear means for transferring the loaded feed table to a position for elevation by said elevating means.

7. In a printing press, a frame, feed table elevating means, a feed table, means for temporarily supporting said feed table in position to be engaged by said elevating means, a feed table support movable laterally of said frame to a position wherein the sheets to be printed may readily be placed on said feed table, and rack and gear means for transferring the loaded feed table to said temporary supporting means.

JOSEPH F. JIROUSEK.
